UNITED STATES PATENT OFFICE.

GUILFORD SMITH, OF SOUTH WINDHAM, CONNECTICUT.

SECURING THE KNIVES USED IN PAPER-PULP-GRINDING ENGINES.

SPECIFICATION forming part of Letters Patent No. 243,733, dated July 5, 1881.

Application filed March 28, 1881. (Model.)

To all whom it may concern:

Be it known that I, GUILFORD SMITH, of South Windham, in the county of Windham, and State of Connecticut, have invented a new and useful Improvement in the Securing the Knives Used in Paper-Pulp-Grinding Engines, which improvement is fully set forth in the following specification and accompanying drawings, in which—

10 Figure 1 is a part sectional and part full view of an engine-cone with the old and my improved mode of securing the knives. Figs. 2 and 3 show an end and side elevation of a knife with my improvement formed upon the same. Fig. 4 is an end view of a knife as applied to the cone of an engine. Fig. 5 is an end view of a knife having my improvement and applied to a cone cut for an old form of knife. Fig. 6 is a part section and part plan 20 view of the cone and knife. Fig. 7 is a side elevation of a knife, showing the means by which the knife is prevented from moving endwise in its slot or recess. Fig. 8 is an end view of the cone containing knives as made and 25 shown in Fig. 2, and also showing the projection *h* as formed on the knife after it has been placed in the recess *a'*.

The object of my invention is to secure a simple and efficient means whereby the knives 30 used in paper-pulp-grinding engines, and particularly those known as the "Jordan" engine, may be securely attached and detached from the cone or shell with the least possible expense and delay.

35 In the drawings I represent the ordinary cone or shell for holding the knives by the letter *A*. The said cone is securely attached to the shaft *B* and driven by any suitable means. Upon the exterior of the cone there are formed 40 a series of ribs, *a*, having radial slots or recesses *a'* cut in them around their entire circumference. In these slots are formed notches *a''*, as shown in Figs. 8 and 6, which are to prevent the knives from being drawn out radially from the slot, as hereinafter described.

45 *E* is a strip of metal of any suitable thickness and depth, and will be designated as a "knife." Upon the knife are formed a series of projections, which may be termed "lips" or "catches," 50 and which may be formed with punches and dies in any well-known manner, such as rolls, di-

rect-acting punches, &c. These lips are designated by the letter *e*, and may all be formed upon one side, as shown in Fig. 1, or on both sides, as may be desired. The knives are also 55 beveled or rounded on the ends, as shown in various views, and are so formed that the pulp may flow freely and not choke up the engine.

To secure the knives from any endwise movement in the slots after they have been placed 60 in position, I form an offset on each knife, as shown at *h*, Fig. 7, which abuts against the sides of the ribs *a* and prevents any movement, as shown. The offset has been formed between the two central ribs on the cone; but said off- 65 set may be formed between any of the other ribs.

The operation of placing the knives in the cone is as follows: In Fig. 1 the knife *E* is shown ready to be placed in position in one of 70 the slots cut in the ribs *a*, the first movement being in the direction of the arrow marked 1. By the second movement, which is in the direction of the arrow 2, the knife, with its lips *e*, is caught under the notches *a''*, thus prevent- 75 ing the knife from being lifted or drawn out radially from the slots when the knives have been placed in position—that is, when the ends of the knives are flush with the ends of the roll. I secure them from any movement end- 80 wise by forming an offset between the two middle ribs by forcing a portion of the metal outward on one side, as shown by the dotted section on line *xx* of Fig. 7. This offset abuts 85 against the ribs and holds the knife from any movement toward either end.

Heretofore the knives have had a portion of the body made heavier and of wedge shape, and when placed in position in the cone had to be driven successively through each of the 90 ribs formed on the cone, this operation being shown at *b*, Fig. 1.

I am fully aware that knives have been made where a portion of the body of the said knife has been cut away to fit over ribs; but this construction greatly weakens the knife and destroys the object which I attain by my improvement. Furthermore, these constructions necessitate special means whereby the knife is held in contact with the roll, such as rings, 95 &c., which are very expensive and occasion a great loss of time in the inserting and taking 100

out of the knives, while with my improvement there are no rings used, and the time taken to secure or release the knife from its recess is insignificant.

5 Having thus fully described my invention, what I desire to claim is—

1. A knife for beating-engines provided with a series of lips upon its side, the said lips being formed by being pressed or forced outwardly, and which adapt the knife to be held in a cone or shell from any radial movement outwardly.

10 2. A cone for beating-engines provided with a series of ribs which are recessed radially and laterally, as and for the purpose set forth.

15 3. A knife for beating-engines having lips formed upon it, and provided with beveled or rounded ends, as and for the purpose set forth.

4. A cone or shell for beating-engines provided with a series of ribs which are recessed 20 radially and laterally, and combined with a knife provided with a series of lips upon its side, as and for the purpose set forth.

5. In a beating-engine, a cone or shell having a series of ribs formed upon it, in combination with a knife having an offset formed upon it, and in contact with and between two or more of the ribs, whereby said knife is prevented from moving toward either end. 25

GUILFORD SMITH.
